UNITED STATES PATENT OFFICE.

JAMES McGRAW, OF WEST ALMOND, NEW YORK.

BINDING FOR BOOKS.

SPECIFICATION forming part of Letters Patent No. 660,304, dated October 23, 1900.

Application filed July 10, 1900. Serial No. 23,135. (No model.)

To all whom it may concern:

Be it known that I, JAMES McGRAW, a citizen of the United States, residing at West Almond, in the county of Allegany, State of New York, have invented certain new and useful Improvements in Bindings for Books; and I do hereby declare the following to be a full, clear, and exact description of the invention, such as will enable others skilled in the art to which it appertains to make and use the same.

This invention relates to bindings for books, and has specific reference to the method of folding the binding and to the rivet by means of which the binding is secured to the mutually-attached leaves.

The object of the invention is to provide a simple and efficient construction which may be readily applied and which when in position will hold the leaves of the book firmly in place.

In the drawings forming a portion of this specification, and in which like numerals of reference indicate similar parts in the several views, Figure 1 is a perspective view showing a book having a cover formed and applied in accordance with the present invention. Fig. 2 is a transverse section taken through the book and one of the securing-rivets. Fig. 3 is a detail perspective view of one of the rivet-heads. Fig. 4 is a sectional view taken through the head of the rivet, a portion of the spring being shown in elevation. Fig. 5 is an end view of the spring which forms the rivet.

Referring now to the drawings, the binding or cover of a book formed in accordance with the present invention consists of a sheet 5 of suitable material, which is folded upon itself to form the front 6 and back 7 of the book, 40 having a connecting-web 8, which forms the back edge of the cover. The front and back of the cover are then folded rearwardly to form layers 9, and finally folded forwardly, so that at the rear edges of the front and back 45 there are three thicknesses of material, as shown. In the rearward folds 9 and the original layers lying therebelow there are formed alining perforations to receive rivets, so that when the leaves are in place they are held directly between the folds 9, and the heads of 50 the rivets are covered by the front and back folds proper. Each of the rivets consists of a helical spring 11, the ends 12 and 13 of which are bent transversely to lie diametrically of

the spring, and the rivet-heads are threaded 55 on these end portions. The rivet-heads each consist of a plate 14, of tin or other suitable metal, having a curvilinear central struck-up portion 15, at opposite points of which are formed alining perforations 17, which are 60 disposed to receive the ends of the helical spring.

In practice the leaves 18 of the book are assembled and perforated for reception of the rivets, and the proper folds of the cover are 65 likewise perforated to aline with the perforations of the leaves, after which one of the helical springs is passed through each series of alining perforations. After the several rivets are in place the rivet-heads are engaged 70 with the ends thereof, the recessed faces of the heads being disposed outwardly, and a drop of solder 15 is dropped into each recess, which by engaging the end of the helical spring holds the latter firmly in place and 75 prevents the displacement of the head.

It will of course be understood that in practice various modifications of the specific construction shown may be made and that any suitable materials and proportions may be 80 used for the various parts without departing from the spirit of the invention.

What is claimed is—

1. A binding for books having retaining-rivets each consisting of a helical spring and 85 rivet-heads each consisting of a plate having a struck-up portion provided with perforations with which the ends of the helical spring are engaged.

2. A rivet for binding books comprising a 90 helical spring having heads, at its ends, each head consisting of a metallic plate having a central struck-up portion provided with alining perforations, the ends of the spring being engaged with the perforations of the heads 95 and lying transversely of the depressions resultant from the struck-up portions, said ends of the spring being held in the perforations by solder deposited in the depressions and clinging to the heads and the ends of the 100 spring.

In testimony whereof I hereunto sign my name, in the presence of two subscribing witnesses, on this 9th day of June, 1900.

JAMES McGRAW.
